ATTORNEY

UNITED STATES PATENT OFFICE

WILLIAM WILLHEIM, OF NEW YORK, N. Y.

DESIGN FOR A TEXTILE FABRIC OR SIMILAR ARTICLE

Application filed October 14, 1932. Serial No. 45,338. Term of patent 3½ years.

To all whom it may concern:

Be it known that I, WILLIAM WILLHEIM, a citizen of the United States of America, residing at 115 Central Park West, in the city of New York, county of New York and State of New York, have invented a new, original, and ornamental Design for a Textile Fabric or Similar Article, of which the following is a specification, reference being had to the accompanying drawing, forming a part thereof.

The figure is a plan view of a textile fabric showing my new design. The design unit consists of that portion shown between the two horizontal dot and dash lines AB and

CD respectively and the two vertical dot and dash lines AC and BD respectively. The upper one half of the design unit has been shown in full lines. The lower one half is a repetition thereof in the relationship wherein the quarter design Y is repeated as indicated at Y¹ and the one quarter design indicated as X is repeated at X¹.

I claim:

The ornamental design for a textile fabric or similar article as shown and described.

In testimony whereof I have signed this specification.

WILLIAM WILLHEIM.
